UNITED STATES PATENT OFFICE

DON N. THOMPSON, OF OWEGO, NEW YORK.

DOUBLE-ACTING BAND-BRAKE.

No. 910,435.

Specification of Letters Patent.

Patented Jan. 19, 1909.

Application filed April 28, 1908. Serial No. 429,700.

To all whom it may concern:

Be it known that I, DON N. THOMPSON, a citizen of the United States, residing at Owego, county of Tioga, and State of New York, have invented a certain new and useful Improvement in Double-Acting Band-Brakes, of which the following is a specification.

My invention relates to a new and useful improvement in double acting band brakes, and has for its object to so construct a brake of this character whereby each end of the band will be fastened to a sliding block moving upon a suitable guide having suitable adjustable stops upon said guide so that the friction between the drum and the band will assist in the operation of the brake.

With these ends in view, this invention consists in the details of construction and combination of elements hereinafter set forth and then specifically designated by the claim.

In order that those skilled in the art to which this invention appertains may understand how to make and use the same, I will describe its construction in detail referring by letter to the accompanying drawing forming a part of this specification, in which—

Figure 1 is a side elevation of my improved brake, and Fig. 2, an end view thereof.

In carrying out my invention as here embodied, A represents a rod the two ends of which are threaded as indicated at B and C also having the key slots D and E formed therein. On the rod A are placed the sliding blocks F and G. One end of the applying lever H is pivoted to the sliding block G at I. A short distance upward from that end of the applying lever which is secured to the sliding block G is secured the forked end of the forked rod J. The opposite end of this forked rod has the thread K cut thereon for threading into the sleeve L, and this sleeve is pivoted to the sliding block F at M.

N indicates the band one end of which is pivoted to the under side of the inner end of the sliding block G as indicated at O, the opposite end being pivoted to the under side of the inner end of the sliding block F at P.

The stop nuts Q and R are threaded on the opposite ends of the rod A and threaded toward one another until the sliding blocks

F and G are brought together as closely as desired so that the band N may be drawn about the drum against which it works as tight as desired. When the nuts Q and R have been brought to their right adjustment a key is placed within the key slots D and E so that the said nuts will be prevented from turning. The nuts S and T are then threaded on the rod A far enough to allow first one end of the rod to be placed in the support U then the other end in the support V when they will be threaded toward the ends of the rod A until they come in contact with the supports U and V for assisting in holding the rod A in place. The nuts W and Y are then threaded on the outer ends of the rod A until they come in contact with the supports U and V thus also assisting in holding the rod A in position.

Of course it will be readily understood that a suitable lever will have to be secured to the applying lever H for operating the brake.

In practice should the drum around which is placed the band N be moving in the direction of the arrow when the band is tightened about it the friction of the band would hold the sliding block F against the stop nut Q and the further movement of the applying lever would move the sliding block G toward the sliding block F thus tightening the band in the direction of the motion of the drum, and in this way securing the friction on the band as an aid to the application of the brake. Should the drum be revolving in an opposite direction the sliding block G would be held stationary and the sliding block F moved toward said sliding block G and the same result secured as in the movement first named.

Having thus fully described my invention, what I claim as new and useful, is—

In a double acting band brake, a rod the two ends of which have threads and key slots cut therein, two sliding blocks adjustably secured on said rod, stop nuts threaded on the opposite ends of the rod for adjusting said sliding blocks, an applying lever one end of which is pivotally secured to one of said sliding blocks, a sleeve pivotally secured to the opposite sliding block, a forked rod one end of which is threaded in said sleeve, the opposite end being secured to the applying lever, a band adapted to pass

around a drum one end of said band being secured to the under side of the inner end of one of the sliding blocks, the opposite end being secured to the under side of the inner end of the opposite sliding block, and nuts for securing the rod to the supports.

In testimony whereof, I have hereunto

affixed my signature in the presence of two subscribing witnesses.

DON N. THOMPSON.
